(57) **CLAIM**

The ornamental design for a thermostat housing, as shown and described.

DESCRIPTION

FIG. 1 is a perspective view of an illustrative thermostat housing;

FIG. 2 is a front elevation view of the thermostat housing of FIG. 1; and,

FIGS. 3-6 are left, right, top, and bottom views of the thermostat housing of FIG. 1.

The portions illustrated in broken lines on the figures are for illustrative purposes only and form no part of the claimed design.
